UNITED STATES PATENT OFFICE

91,349

DESIGN FOR A SHOE

Charles H. Caldwell, Brockton, Mass., assignor to
Geo. E. Keith Company, Campello, Mass., a
corporation of Massachusetts

Application November 16, 1933. Serial No. 49,757

Term of patent 7 years

To all whom it may concern:

Be it known that I, CHARLES H. CALDWELL, a citizen of the United States, residing at Brockton, in the county of Plymouth and State of Massachusetts, have invented a new, original, and ornamental Design for a Shoe, of which the following is a specification, reference being had to the accompanying drawing, forming part thereof.

In the drawing:

Fig. 1 is a side perspective view of a shoe showing my new design; and

Fig. 2 is a rear elevation of the same. Both

sides of the shoe present substantially the same appearance.

The essential feature of the invention resides in the ornamentation of the material of which the shoe is made. As the design is applicable to shoes of various shapes and styles the representation of shoe is merely conventional, for showing an application of the design.

I claim:

The ornamental design for a shoe, as shown and described.

CHARLES H. CALDWELL,
